COMBINED COLD AND HOT WATER SPRAY
AND SHAMPOO FITTING

Charles McKendrick, Edinburgh, Scotland

Application September 3, 1942, Serial No. 457,218
In Great Britain October 2, 1941

1 Claim. (Cl. 137—111)

The subject of the invention is a combined cold and hot water spray and shampoo fitting adapted to be connected to cold and hot water supply systems of unequal or varying pressures, e. g., a cold water main and a hot water tank, the pressure in the cold water main being higher than the pressure in the hot water tank.

An object of the invention is to provide a simple spray and shampoo fitting of improved construction in which the cold water is prevented from entering the hot water system, whereby the possibility of the hot water tank overflowing and causing flooding is prevented.

A combined cold and hot water spray and shampoo fitting, according to the invention, incorporates a T-shaped casing provided with a partition which extends longitudinally through the stem thereof and divides said casing into two L-shaped passages forming respectively a cold water side and a hot water side, the cross limb or head of the T-shaped casing being provided with a cold water stop valve arranged at one end thereof and a hot water stop valve arranged at the other end thereof, and the outer end of the said stem being provided with an end-plate which, on the hot water side, is formed with a port and, on the cold water side, is fitted with a pipe of relatively small bore which extends into a tube that leads to the spraying device or shower rose and which is coupled to the stem of the T-shaped casing.

In operation, when both stop valves are open, cold water is discharged from the cold water side of the fitting through the pipe of small bore into the tube leading to the spraying device in advance of the hot water which enters the said tube from the hot water side of the fitting through the port in the end-plate the cold and hot water supplies mixing in the tube.

Fig. 1 of the accompanying drawing is a side elevation, partly sectional, of a combined cold and hot water spray and shampoo fitting according to the invention, and Fig. 2 is a fragmentary sectional plan view through the line II—II of Fig. 1.

In the drawing 10 is a T-shaped casing presenting a cross-limb or head 11 and stem 12 provided with a partition 13 which extends longitudinally through the stem 12 and divides the casing 10 into two L-shaped passages forming, respectively, a cold water side 14 and a hot water side 15. The cross-limb or head 11 of the T-shaped casing is provided, at one end, with a cold water stop valve 16 and, at the other end, with a hot water stop valve 17. The valve 16 is con-

nected by way of a supply pipe 18 with a cold water pressure supply system and the valve 17 is connected by way of a supply pipe 19 with a hot water supply system.

5 The end of the stem 12 is closed by an end-plate 20 which, on the hot water side 15, is formed with a port 21 and, on the cold water side 14, is fitted with a pipe 22 of relatively small bore. The pipe 22 extends beyond the plug 20 into a tube 23 connected to the stem 12 by a coupling nut 24 and furnished, adjacent to its upper end, with a branch 25 for connection of a tube leading to a spraying device or shower rose.

10 The end of the partition 13, where it joins with the head 11, is formed with curved fillets 26 whereby to direct the water from the valves 16, 17 into the respective sides 14, 15 without back pressure or turbulence.

15 It will be seen that, when both the valves 16 and 17 are open, cold water is discharged from the cold water side 14 through the pipe 22 into the tube leading to the spraying device in advance of the hot water which enters the said tube from the hot water side 15 through the port 21.

20 I claim:

A combined cold and hot water spray and shampoo fitting incorporating a metal T-shaped casting constituted by a tubular cross limb at right angles to a tubular stem, the free end of said stem being externally screw-threaded, two stop valves arranged one at each end of said cross limb, a cold water supply pipe connected to one of said valves, a hot water supply pipe connected to the other of said valves, an end wall at the free end of said stem, a plane partition extending longitudinally through the said stem from said end wall of said cross limb and dividing said casting into two similar L-shaped passages forming, respectively, a cold water side and a hot water side, the said partition being joined to the wall of the cross limb by curved fillets, a tube arranged against the outer face of the said end wall, a screw-threaded coupling nut engaging the screw threads on said stem and serving to secure the said tube to the said stem, an outlet branch which extends laterally from said tube, a pipe of small bore which penetrates the said end wall on the cold water side of the partition, extends through the said tube and the said branch and terminates at the outlet end of said branch, the end wall being formed on the hot water side of the partition with a port to admit hot water to the tube.
